UNITED STATES PATENT OFFICE.

JOHN WAINWRIGHT BOWERBANK, OF KIDDERMINSTER, ENGLAND.

DOMESTIC WASHING APPLIANCE.

Application filed April 5, 1924. Serial No. 704,538.

To all whom it may concern:

Be it known that I, JOHN WAINWRIGHT BOWERBANK, a citizen of the United States of America, residing at Kidderminster, in the county of Worcester, in the Kingdom of England, have invented new and useful Improvements Relating to Domestic Washing Appliances, of which the following is a specification.

10 The invention relates to improvements in domestic washing appliances and aims to provide a device whereby the washing of clothes in a boiler may be greatly facilitated by the violent and continuous circulation of water in said boiler, without necessitating mechanical stirrers or the like.

According to the invention I provide a water circulating device of the kind comprising a dished bottom plate and a tube 20 arising perpendicularly therefrom, comprising in combination a base plate of substantially double conical form, means for securing same adjacent the bottom of the boiler with its apex downwards, perforations 25 around the rim of said plate, an aperture at said apex spaced from said boiler bottom, a central tube arising perpendicularly from said apex within said boiler, a plurality of orifices in said tube remote from said plate, 30 means for retaining the clothes spaced beneath said orifices, and means permitting water to circulate between the clothes and plate.

The invention is more fully described 35 with reference to the accompanying drawings, in which:—

Figure 1 is an elevation partly in section of the device applied to an ordinary copper or boiler; and Fig. 2 is part plan corresponding to Fig. 1, the wire frame 9 being removed for the sake of clearness.

The circular base plate 1 is of double conical form as shown, that is to say, the center portion is conical in shape with its apex downwards, whilst the rim portion presents the form of a frustum of a hollow cone the apex of which is directed upwards. The tube portion 2 being inserted in an orifice at the center of the plate 1 which is raised from the bottom of the boiler, in this case slightly rounded. The plate 1 preferably fits the sides of the boiler, and is furnished adjacent its periphery with a number of small perforations 13, allowing the water to pass beneath the plate from all sides.

The central tube may be formed in a single piece, but preferably it is constituted by two interfitting portions 2, 3 having a helical screw connection of steep pitch whereby the length of the tube may be quickly 60 adjusted as desired. Near the closed upper end of tube portion 3 are symmetrically arranged a number of small radial outlet tubes 4 inclined downwardly and constituting a spray device, the function of which is to direct jets of water upon the clothes which are disposed around the central tube.

A wire frame 9 integral with a sleeve 14 65 slideable on a tube 15 on the upper portion of tube 3 rests upon the upper surface of the clothes and maintains same a correct distance beneath the outlet tubes 4. The upper edge of the sleeve 14 is inclined and co-operates with a similarly inclined lower edge of enlarged portion 16 of tube 15 (which 70 also forms the body portion of the spray device) to give a cam-like action whereby the height of the frame 9 may be adjusted as desired merely by rotating same.

The screw thread may be formed upon 80 tube portion 2 by winding a wire 25 helically thereon and brazing or soldering same in position. The upper tube portion 3 can then be swaged to form a helical groove therein 85 corresponding to the wire, the construction giving economy in manufacture and being effective in use.

The clothes are raised from the base plate 1 and water circulation greatly improved by means of a perforated disk 5 fitting loosely 90 over the tube portion 2 and resting upon the upper rim of the base 1. Where the disk 5 makes contact with said rim it is provided with a number of radiating flutes 6, which each extend from a perforation 7 to adjacent 95 the periphery of said disk, which latter is scalloped in the manner shown and provided with a reinforcing wire edging 8. This construction enables the device to operate in the following manner. When the boiler is heated, the water below the plate 1 quickly becomes hot, rises in the central tube and issues from tubes 4 in jets impinging upon the clothes, which are maintained at the desired level below said jets by means of the frame 9. 100 Water flows through perforations 13 to replenish the space beneath the plate 1 and this sets up a circulation of water from the clothes, through the perforation 7 to below disk 5, and outwardly through flutes 6 to 110

perforations 13. Water also flows around the scalloped edge of disk 5, which serves to keep the clothes clear of perforations 13 and thus a continual and violent circulation of the water is maintained at a steady rate throughout the whole boiler owing to the geyser-like action, and all the clothes are equally treated. Moreover, the water beneath the plate 1 is heated very quickly, so that if a draw-off tap is provided in the bottom of the boiler, very hot water can be obtained whenever desired as is described in the specification of my concurrent application Serial No. 704,539. Steam will also collect beneath said plate and assist in driving water up the central tube, the opening of which is preferably slightly above the level of the perforations 13, though fairly close to the bottom of the boiler.

20 The device can be readily fitted to existing coppers, and in Fig. 1 is shown a convenient method of mounting same. A cross bar 17 spanning the copper is secured by a nut 19 upon screw pin 18 on the closed upper end of tube 3. The ends of the bar are slotted and engage set-bolts 19 screwed into the rim 20 of the copper, and clips 21 pivoted on said bolts retain the bar in position. The extensible tube 2, 3 enables the device to be adjusted to different sizes of boiler or quantities of clothes.

I claim:

1. A device for use with domestic washing appliances comprising in combination a base plate of substantially double conical form perforated around the rim and apertured at the apex, means for securing same adjacent the bottom of the boiler with its apex downwards and, spaced from said boiler bottom, a central tube arising perpendicularly from said apex within said boiler, and carrying a spray device at its upper end, means for retaining the clothes spaced beneath said spray device, and means to permit the circulation of water between said clothes and plate.

2. A device for use with domestic washing appliances comprising in combination a base plate of substantially double conical form perforated around the rim and apertured at the apex, means for securing same adjacent the bottom of the boiler with its apex downwards and spaced from said boiler bottom, a central tube arising perpendicularly from said apex within said boiler, a plurality of outlet tubes in said central tube remote from said plate, means for retaining the clothes spaced beneath said orifices and a perforated and radially fluted disk superposed upon said base plate and spacing the clothes therefrom.

3. A device for use with domestic washing appliances comprising in combination a base plate of substantially double conical form perforated around the rim and apertured at the apex, means for securing same adjacent the bottom of the boiler with its apex downwards and spaced from said boiler bottom, a central tube arising perpendicularly from said apex within said boiler, a plurality of outlet tubes in said central tube remote from said plate, a frame slideable on said central tube retaining the clothes spaced beneath said outlet tubes means for adjusting the upward limit of movement of said frame, and a perforated and radially fluted disk superposed upon said base plate and spacing the clothes therefrom.

4. A device for use with domestic washing appliances comprising in combination a base plate of substantially double conical form perforated around the rim and apertured at the apex, means for securing same adjacent the bottom of the boiler with its apex downwards and spaced from said boiler bottom, a central tube arising perpendicularly from said apex within said boiler, said tube comprising two interfitting tubular portions screw threaded along the whole length thereof, a plurality of outlet tubes in said central tube remote from said plate, a frame slideably on said central tube retaining the clothes spaced beneath said outlet tube, means for adjustably limiting movement of said frame, and a perforated and radially fluted disk superposed upon said base plate and spacing the clothes therefrom.

5. In a domestic boiler, a device comprising in combination a base plate of substantially double conical form perforated at the rim and apertured at the apex said apex being directed downwards and spaced from said boiler bottom, a central tube arising perpendicularly from said apex within said boiler, said tube comprising two interfitting tubular portions, screw-threaded along the whole length thereof, a cross-bar secured at the center to said tube and spanning the boiler, a pair of clips on said boiler releasably retaining the ends of said bar, a plurality of outlet tubes in said central tube remote from said plate, a frame slideable on said central tube retaining the clothes spaced beneath said outlet tubes, means for adjustably limiting movement of said frame, and a perforated and radially fluted disk superposed upon said base plate and spacing the clothes therefrom.

JOHN WAINWRIGHT BOWERBANK.
